UNITED STATES PATENT OFFICE.

MILTON BARTLEY, OF PITTSBURGH, PENNSYLVANIA.

RAILWAY-TRACK CONSTRUCTION.

1,107,018.

Specification of Letters Patent. Patented Aug. 11, 1914.

Application filed May 20, 1914. Serial No. 839,744.

To all whom it may concern:

Be it known that I, MILTON BARTLEY, a citizen of the United States, residing at Pittsburgh, in the county of Allegheny and State of Pennsylvania, have invented certain new and useful Improvements in Railway-Track Construction, of which the following is a specification.

My invention relates to improvements in railway track construction, and particularly to means for positively maintaining the guard rails of switches, crossovers, etc., in fixed positive relation to the main rails of the track, and especially at positions opposite the crossover point of the ordinary frog construction, for the purpose of insuring alinement of the wheel treads therewith, and preventing any variation in passing over the space between the frog point and the main rail.

The invention is also adapted to the protection of the main rails of a track against spreading, at switch junctures, one embodiment of the invention being illustrated in such application.

The invention consists generally in providing, with the frog and the opposite guard rail for the companion track rail, or with the outer track rails of a switch construction, means for fixedly holding the guard rail in relation to the outer track rail and the frog construction, or for maintaining the outer rails, of a switch, in fixed unvarying relation and uniform gage.

Ordinarily, guard rails, or track rails at switches, are merely held in position on the cross ties, and with relation to the inner side of the outer rail, in the case of a guard rail, by shoes, clamps or braces of different form, either spiked to the tie, or connected in some manner, as by an embracing clevis with the outer rail.

My invention provides positive bracing means between the frog construction, or the outer rails thereof, and the guard rail for the opposite companion rail; or between the outer rails of a switch, independent of the movable switch point, such means consisting generally in resisting or bracing members

and intervening sectional body portions, 50 operable either as strut members or tension members, having adjustable mechanism for clamping the rail braces and engaging portions into holding engagement against the track members, also intermediate independent length adjusting members, the construction being intended to also engage a supporting tie.

Preferred forms of the construction are shown in the accompanying drawings, in 60 which—

Figure 1 is a plan view of a railroad crossover provided with the usual center frog construction, the outer track rails, and their guard rails, showing one form of the 65 invention as applied. Fig. 2 is an enlarged longitudinal sectional view on the line II. II. of Fig. 1. Fig. 3 is an enlarged detail plan view of the construction illustrated in Fig. 2. Fig. 4 is a plan view, similar to 70 Fig. 1, showing the invention as applied to a switch. Fig. 5 is an enlarged longitudinal sectional view on the line V. V. of Fig. 4. Fig. 6 is a cross sectional detail view, enlarged, taken on the line VI. VI. of Fig. 3, 75 showing the adjustable wedge. Fig. 7 is a similar sectional view, showing a modified detail construction of the locking wedge. Fig. 8 is a cross sectional detail view on the line VIII. VIII. of Fig. 3.

In the drawings, referring to Sheet 1, the main inner track rails 2, 3, converge and form continuations of the tread surfaces of frog member 4, of the usual frog, having at each side the customary guard rail members 5 and 6 respectively, of well-known construction. Rails 2 and 3 are parts of the two main tracks, composed of the rails 2 and 2' respectively, and 3 and 3' respectively. The guard rails 5 and 6 of the frog member converge toward the point *a* between which and the point *b* of the frog is the intervening open space *c*. The treads of the wheels, as is well-known, run across such open space and off of the main track rails 2 and 3 respectively and onto the point *b* of the frog 4, or vice versa from either side, and it is highly important that the treads and flanges of the

wheels shall cross this space accurately and surely to insure safety and free trackage. For such purpose, the guard rails 7 and 8 respectively are ordinarily laid along the inner side of the opposite rails 2' and 3' respectively, and opposite the middle portion of the frog which is to be protected, extending to a considerable distance at each side thereof, as is the usual practice. For the purpose of firmly and fixedly bracing the guard rail members 7 and 8, I provide the construction shown in Figs. 1, 2 and 3 of the drawings, and indicated generally by the letter A, referring generally to the complete composite member extending between one main track member and the other. In such case the member A constitutes a bracing spanner or member composed of two connected plate members 9 and 10 respectively, each having opposed inner terminal abutments 11 and 12 respectively, fitting against the head, web and flange of the innermost rail at each side, *i. e.*, rail section 6 of the frog at one side and guard rail 8 at the other side. Abutment 11 is fixedly secured to plate 9 by bolts 13, and abutment 12 is adjustably secured to plate 10 by similar bolts 14. Said bolts may be tapped directly into the plate 10 or may be provided with nuts on the under side; preferably recessed in the same manner, as are the nuts shown in Figs. 6 and 7. The inner adjacent connecting ends of plate members 9 and 10 are each provided with an upwardly extending flange or wall 15, said flanges being fixedly connected together by intervening bolts 16. Said bolts, preferably two for each joint, are provided with adjusting nuts 17, whereby each flange may be positively engaged and fixedly located or spaced apart, or accurately adjusted, as desired. For the purpose of insulating one of the plate members and its parts from the other, one of the flanges 15 is provided with insulating thimbles and washers, of well-known construction, as indicated at 18, and more particularly illustrated in Fig. 5. By this means, the passage of electric currents from one member to the other is prevented. For the purpose of providing supplemental adjustment for one of the abutments 12, its rear end is chamfered or tapered crosswise, as indicated at 19, and between such edge and the inner face of flange 15 is interposed the wedge member 20, for the purpose of accurately adjusting the abutment 12 toward or from the rail 8. Wedge 20 is secured in position by a bolt 21 extending through a longitudinal slot 22 of the wedge, such bolt being either tapped into the plate member 10, as in Fig. 2, or into a nut 23, preferably recessed into the under side of member 10, to prevent turning, as shown in Fig. 6. As an additional holding means for wedge 20, against receding from engagement with face 19 of abutment 12, it

is provided with a series of transverse shoulders 24, one of which is adapted to engage over the edge of plate member 10 when the wedge is adjusted and screwed down in place, thereby fixedly holding it against movement. 70

In Fig. 7 I have shown a modified construction of wedge 20', mounted upon plate member 10' by means of the bolt 21' and nut 23', above described, but provided at its narrowed end with a pivoted locking dog 24^a having a series of locking shoulders 24', and rotatably mounted on a pivoting pin 24^b, within a slot 24^c, and provided with an upwardly extending operating finger 24^d. By such construction the same securing hold may be had against the edge of the plate member 10'. A filler block 25 is interposed at intervals between the guard rail 8 and track rail 3', preferably with one or more liners 26, whereby to firmly brace the rails apart and provide for setting the guard rail up toward the main rail, when its inner face becomes worn, by removing the liner, which may be of any degree of thickness. 75 80 85 90

In the switch construction, illustrated on Sheet 2 of the drawings, the outer track rails 2^a and 3^a are provided with the inner adjustable switching rails 27, 28, tapering to switch points, of well-known construction, and provided with connecting members 29 and an operating rod 30 for shifting the switch points. Plate members 9^a and 10^a, of generally similar construction to members 9 and 10 above described, are also provided with adjacent upwardly extending flanges 15^a, and connected by the same adjusting bolts 16^a and their nuts, as above described. The plate members, however, each extend underneath the rails 2^a and 3^a, and are provided at their outer ends with lug members 31 and outer abutments 11^a and 12^a. Said abutments engage against the outer head, wedge and flange of the rails 3^a and 2^a, as shown, and also against the outer abutments 31, and are fixedly secured in position by bolts 32, thus providing substantial reinforcements against the outer side of each rail. Inwardly of each rail 2^a and 3^a is a supplemental plate 33, preferably secured to the plate member 9^a or 10^a by one or more bolts 34, or in any other suitable manner, whereby to facilitate reinforcing engagement against the inner flange of rails 2^a and 3^a. Upon plates 33, as thus provided, are slidably mounted switch rails 27, 28, respectively, adapted to be moved in either direction by the usual operating mechanism. 105 110 115 120 125

The construction as above described is substantially the same as that for the cross-over, except that it eliminates the supplemental wedge member 20, but embodies intervening adjusting and holding bolts, whereby to fixedly locate the members with relation to each other. It will be understood 130

that the plate member in either case is secured to the usual cross tie, with any suitable bolt or spike construction. Where a pair of bolts are provided, as indicated in Fig. 8, such bolts 35 may be tapped into twin nuts 36, preferably recessed up underneath the under side of member 9, whereby to effectually prevent turning of the nut on loosening of the bolt.

10 With either of the constructions described, it will be seen that the plate members provide a good supporting foundation for the rails; that the abutments by engaging the rails will positively and effectually brace them against movement; that the adjustability of the abutments and the positive securing of them in position will effectively hold and maintain the rail member in positive position, so as to resist pressure and 15 strains and carry out the objects of the invention.

The advantages of the improvement will be readily appreciated by all those familiar with this class of apparatus. It insures 20 positive and permanent spacing and maintenance of the guard rails, or of the main rails when used with a switch; it provides for immediate and easy adjustment, so that any wear of the rails by the wheel flanges 25 may be compensated for; and is simple in construction, strong and reliable, and not liable to get out of order.

The device may be variously changed or modified by the skilled mechanic in various 30 features of detail construction, but all such changes are to be considered as within the scope of the following claims.

What I claim is:

1. The combination with a railway frog, 40 an opposite track rail, and a protecting guard rail therefor; of bracing abutments directly engaging the web of the frog and guard rail respectively, and an intervening bracing mechanism composed of a pair of 45 tandem plates having adjacent flange portions, bolts connecting said portions provided with adjusting nuts, the outer portions of said plates extending underneath the rail structure and each provided with a 50 bracing abutment fixedly secured to its upper surface and engaging the rail structure, one of said plates having an adjustable abutment and a wedge bearing directly against the plate flange, substantially as set forth.

55 2. Rail bracing mechanism comprising a plurality of supporting plates in tandem arrangement adapted to be laid upon the upper surface of a tie and each having an inner connecting flange, said plates extending by 60 their outer portions underneath the rails and provided with rail bracing abutments, one of said abutments being longitudinally adjustable upon one of said plates, and an adjustable wedge for holding said abutment 65 fixedly in position bearing directly against

the end of the abutment and the plate flange respectively, substantially as set forth.

3. In an apparatus of the class described, the combination of two longitudinally arranged supporting plates adapted to be laid 70 upon a railroad tie, each having an inner flange, bolts adjustably securing said flanges together, a rail bracing abutment fixedly secured to one of said plates, a rail bracing abutment adjustably secured to the other of 75 said plates extending inwardly adjacent to its inner flange and a wedge device adjustably inserted between the inner end of said abutment and the flange of the plate and bearing directly against it, substantially as 80 set forth.

4. In an apparatus of the class described, the combination of two longitudinally arranged supporting plates adapted to be laid upon a railroad tie, each having an inner 85 flange, bolts adjustably securing said flanges together, a rail bracing abutment fixedly secured to one of said plates, a rail bracing abutment adjustably secured to the other of said plates extending inwardly adjacent to its inner flange a wedge device adjustably inserted between the inner end of said abutment and the flange of the plate and bearing directly against it and means for adjusting and fixedly holding said wedge in 90 95 position, substantially as set forth.

5. Guard rail bracing mechanism of the class described consisting of a pair of rail supporting plates adapted to be laid upon a tie having inner adjacent connecting flanges 100 and adjusting securing bolts extending therethrough, one of said plates having at its outer end an outwardly pressing rail bracing abutment, the other of said plates having at its outer end an inwardly extending 105 pressing bracing abutment, and an inner outwardly bracing abutment adjustably secured to the plate, and means interposing resistance therefor bearing directly against the connecting flange of the plate, substantially 110 as set forth.

6. Guard rail bracing mechanism of the class described consisting of a pair of rail supporting plates adapted to be laid upon a tie having inner adjacent connecting flanges 115 and adjusting securing bolts extending therethrough, one of said plates having at its outer end an outwardly pressing rail bracing abutment, the other of said plates having at its outer end an inwardly extending 120 pressing bracing abutment, an inner outwardly bracing abutment adjustably secured to the plate, and an adjustable wedge device interposed between it and the connecting flange of said plate and bearing directly against said flange and means for holding said wedge in position, substantially 125 as set forth.

7. In mechanism of the class described, the combination with the supporting plate 130

and an adjustable rail bracing abutment thereon, of a holding wedge operable against said abutment and provided with a securing bolt, and having a plurality of transverse shoulders for individual engagement with the edge of the plate, substantially as set forth.

In testimony whereof I hereunto affix my signature in the presence of two witnesses.

MILTON BARTLEY.
